UNITED STATES PATENT OFFICE.

ALPHONSE PELTIER, OF BROOKLYN, NEW YORK.

BOTTLE-STOPPER.

SPECIFICATION forming part of Letters Patent No. 789,058, dated May 2, 1905.

Application filed December 27, 1904. Serial No. 238,398.

To all whom it may concern:

Be it known that I, ALPHONSE PELTIER, a citizen of the United States, and a resident of the borough of Brooklyn, in the county of 5 Kings and State of New York, have invented a certain new and useful Bottle-Stopper, of which the following is a specification.

This invention relates to a stopper made of glass or other material for bottles or other 10 vessels. Its organization comprises a valve with means whereby said valve closes a port when it is attempted to fill the bottle or vessel to which the stopper has been applied, the same means allowing the valve to open the 15 said port when it is to empty the bottle or vessel of the fluid or liquid that may be contained therein.

More specifically, the invention consists of a chamber with outlets at one end and a port 20 at the other, over which latter a valve can be seated by gravity or by the action of a fluid or liquid entering the said openings. The valve may be lifted or raised by a fluid passing through the said port on its way out of 25 the said bottle or vessel.

Referring to the drawings, Figure 1 represents a vertical axial section of the stopper attached to the neck of a bottle. Fig. 2 shows a top view of the stopper. Fig. 3 is a top 30 view of the chamber of the stopper. Fig. 4 represents a partial section as on the line $x-x$ of Fig. 3. Fig. 5 is a section of Fig. 1 on the line $x'-x'$. Fig. 6 represents a partial axial section of a modification of the invention. 35 Fig. 7 shows a top view of the valve represented in Fig. 6.

Referring to Figs. 1 to 5, the neck of a bottle is shown at A, on the top edge of which is supported a chamber B by means of a flange 40 b extending therefrom. At the lower end of the chamber there is formed a valve-seat b' , with the port b^2 . Rings or helical indentations b^3 are generally formed on the outer surfaces of the chamber to hold cement C, with 45 which the chamber is securely fastened to the neck of the bottle. A threaded collar b^4 extends up from the flange b and to which is screwed and held with cement the cap D, having the openings or perforations d . At the 50 top end of the chamber B is fastened the head

or plate E, having perforations or openings e . A lug E' extends from the circumferential edge of the plate E, and a notch b^5 on the inner circumferential edge of the opening in the top of the chamber B is arranged to allow the 55 said lug to pass therethrough into a groove b^6 in said chamber. After the lug has been turned or moved into the groove a small portion of cement placed into the notch will keep the head or plate E in place. A guide-barrel E² extends from the plate E and envelops the spindle f of the valve F. The latter is generally made spherical on its seating-face to securely fit its seat b' , which latter is shaped to suit the said valve. The lower end of the guide-barrel E² is generally flared out or turned up, so as to constitute a table E³, and the valve-seat b' is turned in at its upper end to form a table B'.

To apply and use the invention, the valve 70 F is dropped in place on its seat b' . Then the plate E is secured to the chamber B, after which the cap D is fastened on the said chamber. Then the latter is inserted into the neck 75 A of the bottle, the flange b being supported on the edge of the said neck, and a portion of cement between the chamber and surface of the neck bind them securely together.

It is evident that when the bottle, with its stopper, is held in an upright position, as 80 shown in Fig. 1, the valve F covers the port b^2 and that any fluid forced through the perforations in the cap D and plate E will tend to more securely hold the valve F on its seat. Should by any accident the valve not 85 be located over the port, then the liquid which will be trapped in the top of the cup-shaped valve F will force the latter into proper position to close its port b^2 . Should any instrument be inserted through the perforations d or e in an attempt to lift or hold up the valve 90 F, the latter cannot be reached, because the tables E³ and B' would prevent the same. When the bottle is tipped and inverted, the valve F falls away from the seat b' , opens the 95 port b^2 , and allows the fluid or liquid to flow through the perforations d and e .

In Figs. 6 and 7 the invention is modified by dispensing with the barrel E² and inserting in a chamber G, otherwise similar to the 100

chamber B, a valve H, which latter has extending below it the stem h , that carries the table H', having the prongs h^2 . In this modified form of stopper the valve H covers the 5 port I of the seat g in the chamber G, and when the bottle J is tipped and inverted the valve H falls away and opens the said port I, the prongs h^2 preventing the table H' closing the said port, and hence the fluid or liquid 10 contained in the bottle can be poured therefrom.

Having described my invention, I claim—

1. In a stopper the combination of a chamber, a valve-seat having a port in the chamber, a valve in said chamber, a guide in the chamber to maintain the valve in proper positions, a table extending from the guide, and a cap having perforations on the chamber.
2. In a stopper the combination of a chamber, a valve-seat with a port in the chamber, a valve in said chamber, a guide in the chamber to maintain the valve in proper positions, a table extending from the guide, a table extending from the valve-seat, and a cap having 25 perforations on the chamber.
3. In a stopper the combination of a chamber, a valve-seat having a port in the chamber, a perforated head at the top of the chamber, a barrel-guide extending from the head, a valve in the chamber arranged to operate 30

over the port in the chamber, a spindle on the valve extending into the barrel-guide, and a perforated cap secured to the chamber.

4. The combination of a vessel, a chamber secured thereto, a valve-seat having a port at 35 one end of the chamber, a perforated head at the other end of the chamber, a barrel-guide extending from the head, a valve in the chamber over the said port, a spindle on the valve extending into the barrel-guide, and a perforated cap over the chamber.

5. The combination of a bottle, a chamber secured in the neck thereof, a valve-seat having a port at the lower end of the chamber, a perforated head secured to the top of the 45 chamber, a barrel-guide extending from the head, a cup-shaped valve in the chamber over the said port, a table extending from the barrel-guide, a table extending from the valve-seat, a spindle on the valve extending into the 50 guide-barrel, and a perforated cap on the chamber and extending beyond the neck of the bottle.

Signed in the borough of Manhattan, in the county of New York and State of New York, 55 this 21st day of December, A. D. 1904.

ALPHONSE PELTIER.
